UNITED STATES PATENT OFFICE.

EDWARD C. ALBREE, OF SWAMPSCOTT, MASSACHUSETTS.

ACCOUNTING SYSTEM.

No. 902,544.

Specification of Letters Patent.

Patented Nov. 3, 1908.

Application filed February 28, 1906. Serial No. 303,418.

To all whom it may concern:

Be it known that I, EDWARD C. ALBREE, a citizen of the United States, residing at Swampscott, county of Essex, State of Massachusetts, have invented a certain new and useful Improvement in Accounting Systems, of which the following is a specification, reference being had therein to the accompanying drawings.

10 In factories and similar places, it is frequently desirable to know exactly what is the cost of the labor and material which go to make up the cost of the various articles produced. In such cases, it is desirable that 15 the results required be accurate and be obtained as quickly as possible and with the least possible expenditure of labor. Such systems are denominated "cost accounting systems," and are frequently very complicated and expensive to maintain, especially 20 where the factory is a large one. Many persons are frequently employed in a large factory in keeping the cost accounting system, and this labor is entirely "unproductive," 25 that is, it does not contribute directly toward the production of the goods. It is, therefore, desirable that such systems be as simple as is consistent with obtaining the required results in order that the expense may be as 30 small as possible. It is also desirable that the workman have as little to do with the system as possible, because workmen are frequently illiterate or slow to comprehend and perform their part of an accounting system.

35 My invention has for its object to produce a cost accounting system which may be adapted to all kinds of factories and similar places and which will be inexpensive to put into operation and to maintain.

40 My system has the advantage that it may be used with equal success even when the workmen are illiterate, because the workman is not required to read or write anything. It also has the advantage that no mental operation is required to be performed in making the entries upon the cards comprising my system other than that of finding and marking the proper place and punching or marking the cards simultaneously at this point, 45 the total being thereby determined and entered upon the cards without further mental or physical operation.

When my system is employed, there can be no discrepancy between the total amount paid the workmen and the amount charged

to the various jobs for labor, because the workman's pay depends directly upon the amount which has been charged for labor to the various jobs upon which the workman has been employed. The same is also true of the materials used.

In the accompanying specification, I have described my invention in the form in which it may be used in a factory, but it may be used with equal success in warehouses, 65 stores and many other similar places by slight adaptations such as may be made by any person skilled in the art.

My invention has a wide range of usefulness which I will not describe further here. 70

In this specification I have described a number of special features which I believe to be patentable and which I intend to make the subject matter of subsequent applications.

In the following specification, I have described my invention as embodied in properly divided and printed cards which are superposed and punched to record the desired data, but the invention is also capable of embodiment in other forms such for instance as that in which detachable coupons are employed. I do however prefer the form described in this application, as this form is more convenient to use and is not affected by certain mechanical limitations 80 which are imposed upon other embodiments by their structure. Both systems embody my invention which is, I believe, capable of other and further modification.

My system depends largely for its success 90 upon the fact that it is substantially a double-entry system, each charge or entry appearing in two or more places which serves to check both entries and insures accuracy. This result is accomplished by the employment of cards in pairs which are punched simultaneously. One of the cards of the pair, I call for convenience the primary card. It may be in different forms according to the kind of information which it is intended to 95 record as for instance workmen's time cards, piece work cards, and material cards. The other card of the pair is called the secondary or record card, and also may be in various forms of which the job card is that most 100 commonly used. Either or both of the cards of the pair of cards may be duplicated, the duplicates being punched simultaneously 105 but I have not thought it necessary to show these.

The primary cards form the vouchers for the workman's pay and for the materials required, and the secondary cards show the charges which are made to the various jobs. 5 As the entries upon the primary and secondary cards are always duplicates of each other it follows that all the money paid to the workman for labor or spent for material is charged to the various jobs upon which it has 10 been expended.

The cards employed in my improved system may be of different sizes, although it is convenient to have them uniform in size, but each card is ruled or divided into spaces 15 which are multiples of a unit space which is uniform in size in all the cards comprising the system. The spaces on the cards are arranged in columns of equal height, and this equality of height of all the columns of spaces 20 is thought to be essential to the best working of the system where punch marks are employed to designate particular points upon the cards.

The invention also includes the method of 25 determining and recording amounts upon the cards.

The invention will be readily understood from the following description taken in connection with the accompanying drawings, 30 and the novel features thereof are pointed out and clearly defined in the claims at the close of the specification.

In the drawings,—Figure 1 shows the face of a workman's time card for a workman receiving \$.05 per hour. Fig. 2 shows the back face of the card shown in Fig. 1. Fig. 3 shows a workman's time card for a workman receiving \$.02½ per hour. Fig. 4 shows a workman's piece-work card. Fig. 5 shows 40 a material card. Fig. 6 is a view of a job card. Fig. 7 shows the card A superposed on the card I in position for punching as described. Fig. 8 shows the card A superposed upon the card I with the punch-mark 45 J in registration with the first unit space of the card I. Fig. 9 is a view of a workman's card provided with a subtraction dot. Fig. 10 shows a subtraction card. Fig. 11 shows the subtraction card Q superposed upon the 50 workman's time card P, in position for punching.

In the following description of my invention and the operation thereof, I will describe the same as applied to a factory in which 55 work begins at seven o'clock and continues until six o'clock with an intermission of one hour from twelve to one o'clock. Some of the workmen are paid by the hour and others by the piece. I will take up first the primary card in its various forms, and then the secondary or record cards.

Referring first to Fig. 1, there is shown a workman's time card A to be used by a workman paid by the hour, who receives 65 \$.05 per hour. The card is divided into

unit spaces B of uniform height and breadth, arranged in columns of fifty spaces each, the said columns being of equal height and width. For convenience in reckoning, the unit spaces B are further divided into groups 70 of five by heavier division lines. Every unit space B represents a value of one cent, and this standard of value is uniform throughout all the cards which are employed together. The unit spaces B are commonly 75 based upon some standard of monetary value as for instance in this case upon the cent. Under these circumstances they may be called "money" unit spaces, but in certain cases the unit may be some other concrete thing as for instance pairs in a shoe factory. This change in the standard of value and in the name of the spaces does not affect the substance or operation of the invention. The card A is provided with sufficient spaces 80 to keep the record of a week's work upon. It will be seen that the card is somewhat wider than is necessary to provide space for one week's work by a workman receiving five cents per hour. This waste space may be 85 employed when the rate of pay is greater. At regular intervals determined by the amount per hour which the workman receives, are placed letters and figures C indicating the days of the week and the working hours of each day. For convenience of 90 description, these letters and figures C are hereafter termed "hour numerals". On the card A shown in Fig. 1, M⁸ is placed in the fifth space from the bottom of the card in the 95 right hand column; M⁹ in the tenth space; and so on, the proper hour numeral being placed in each space whose number counting from the lower right hand corner of the card is a multiple of five. Should the workman 100 receive some other sum, as for instance eight cents per hour, that sum becomes the number whose multiples determine the location of the hour numerals. As Tuesday and Thursday begin with the same initial letter, 105 I employ the arbitrary letters E and U in the spaces corresponding to those days to prevent confusion.

An example of another rate of pay is to be found in Fig. 3, where a card D intended for 110 use by a workman receiving two and one-half cents per hour is illustrated. In that case the hour numeral M⁹ is placed in the fifth space from the bottom, M¹¹ in the tenth space, and so on. The inspector or other 115 person to whom the card goes to be punched can readily estimate the intermediate distances, so it is not found necessary to put the intermediate hour numerals on the card.

The back side of the card is divided into 120 spaces in exactly the same manner as the front side, the said spaces on the front and back sides registering with each other, and the spaces on the back of the card are provided with numerals which indicate the total 125

value in money of the preceding spaces. In Fig. 2 these numerals are shown at E. They begin at the lower left hand side of the card A so that they may apply properly to the 5 spaces on the face of the card which begin at the lower right hand corner, as seen in Fig. 1. These numerals are located in the space next above the space to which each applies in order that they may not be destroyed by the punch marks which are made 10 upon the cards. These numerals are called for convenience "total figures" and form an arithmetic series, that is a series any term of which is obtained by adding a fixed 15 amount to the preceding term. It is sometimes more convenient to have these total figures on the face instead of on the back of the card, in which case they are arranged as shown at F in Fig. 3 adjacent the proper division lines.

Primary cards for piece work, *i. e.* work where the workman is paid by the piece instead of by the hour, are arranged in a substantially similar manner except that the 20 hour numerals are replaced by other numerals indicating the number of pieces which the workman has made, these numerals being applied to the cards according to the number of unit spaces represented by the price to be 25 paid to the workman per piece or per hundred pieces. Such a card is shown in Fig. 4, the price being three and one-half cents per piece. In this case the numbers 2, 4, 6, etc., indicating the number of pieces, are placed 30 upon the cards at every seventh space, this being a convenient manner where a fractional amount per piece is paid. If it is not desired to have the card encumbered by so many figures, corresponding numbers may 35 be put on at less frequent intervals. The back side of the piece work card G is provided with total figures exactly as are the workman's time cards, the proper total figure being applied to every fifth space as has 40 already been described. I have not, therefore, thought it necessary to illustrate this in the drawings or to describe it further in the specification.

A third kind of primary card is used for 45 keeping a record of the material which enters into the various jobs. In Fig. 5, such a card is shown. It is divided into unit spaces in the same manner as the other primary cards heretofore described. Groups of these 50 unit spaces are provided with figures in the same manner as are the workman's time cards and piece work cards. Thus, in the card shown in the figure which is intended to be used for material worth four cents per 55 pound, the numeral 1 is applied to the fourth space from the bottom, the numeral 2 to the eighth, etc.

Having described various forms of primary cards, I will now describe some of the 60 secondary cards in connection with which the

primary cards are employed. These are also called job cards when used for that specific purpose. The job card I, see Fig. 6, is divided into unit spaces, and total figures are applied thereto as previously described, but 70 a space I' is left at the bottom of the card for a purpose to be described later, and a margin I² one space in width is also left on the right hand side of the card.

A separate job card is employed for every 75 operation and lot of material, and upon it is kept the record of the labor performed by the various workmen or of the material which enters into the production of the finished product.

When the workman enters the factory in the morning, if he is at work by the day, he receives a workman's time card, having an unpunched value equal to the maximum amount which he can earn in a week, and on 80 reaching his station, receives from the foreman the job card for the job upon which he is to begin work. When he completes the work, for instance, at eleven o'clock, he goes to the inspector, taking with him his time 85 card and the job card. The inspector places the time card A upon the job card I with the lower right hand corner of the time card registering with the bottom line of the unit spaces, and then punches both cards when in 90 this position at M¹¹ as shown at J in Fig. 1 and J' in Fig. 6. He may also write upon the workman's time card near the hole which he has just punched the characters 45B which is the number of the job card which 95 was punched simultaneously with the workman's time card; and upon the job card adjacent the punch mark J' the number 27, which is the number of the workman's card which was punched at the same time. The two 100 cards then show that the workman No. 27, to whom the primary card belongs, has worked until eleven o'clock on job 45B, and that in so doing he earned \$.20, as seen by the total figures on the back of the card, see Fig. 2. 110 Inspection of the job card I shows that workman 27 has expended \$.20 worth of time on this job. It will be seen, therefore, that the amount of pay due the workman for this work has been figured out; that is to say, 115 four hours labor at \$.05 an hour, making a total of \$.20. These results are reached without any mental or physical operation other than that of placing the two cards together in proper position and punching them 120 at the time at which they are brought to the inspector, namely at eleven o'clock. Furthermore, this single operation has recorded upon both the primary and the secondary cards the same information, each forming a 125 check on the other. The workman then starts on another job, *viz.*—that represented by another job card. When his work on this job is completed, he again goes to the inspector who places the primary card on the 130

secondary card with the last punch mark J (see Fig. 8) in registration with the lower marginal space I' of the secondary card, and punches both cards at the point indicated by 5 the hour numeral on the primary card corresponding to the time at which the card is presented. In Fig. 8, this time is represented as 3 p. m. on Tuesday, and the punch mark is designated M. This operation adds 10 to the total of \$.20, which the workman has already earned, \$.65, and the card then shows that his total earnings to this point have been \$ .85. There is shown on the card A of Fig. 1 two other punch marks N and O which show 15 that this workman worked on two more jobs during the week and at 6 p. m. Saturday had earned \$3.00 having worked 60 hours at \$.05 per hour.

As the operation of the other primary 20 cards is similar to what has already been described, I have not thought it necessary to describe them further in detail.

Thus far in describing my accounting system, the operations have been additions, 25 that is to say, the amount which a workman has earned on one job has been added to the amount already earned and previously recorded upon the card. It is, however, frequently desirable to be able to make sub- 30 tractions from the amounts already recorded on the cards. My system affords means by which this may be done with the same ease and convenience as the additions previously described are made. If a workman has been 35 sick or absent from the factory for any reason, it is convenient to make such a subtraction. As has been previously stated, the last punch mark on the workman's card indicates at the end of the week the amount of pay which he 40 is to receive, and to indicate to the cashier or auditor the total amount of money to be paid to a workman for the work recorded on his time card I find it convenient to indicate this point by a punch mark of special design. 45 The spaces before this special punch mark may be said to be active or used spaces, that is the cashier will pay the workman the amount of money represented by the used spaces. The spaces after the mark may be 50 called unused or inactive spaces.

For convenience in subtracting amounts from a workman's card, as for instance for sickness or absence from the factory, I place a mark which for convenience I call a subtraction dot in the space next above the last 55 space of those which would be used by the workman if he were at the factory the entire week. The process of performing the subtraction is as follows:—When the workman 60 returns to work, after being absent for any reason, he takes his workman's card P, see Fig. 9, to the inspector who superposes it upon a card Q called a subtraction card, such as is shown in Fig. 10, with the last punch mark 65 R (the workman having already earned \$1.35

as shown on the card P) on the marginal space I'. The inspector then punches both cards at the hour on which the workman has come to him, as for instance as S and S' on the cards P and Q respectively. The subtraction card Q then shows the man has lost the sum indicated by the total figure by being absent. In the drawings, this amount is \$ .65. It is necessary that this amount be deducted from the primary card as otherwise 70 the workman would be overpaid at the end of the week. To do this the inspector places (see Fig. 11) the subtraction card Q upon the primary card P with the punch mark S' in registration with the subtraction dot R'. The 75 subtraction mark is not absolutely necessary because it is possible to superpose the cards without this mark for a guide, but I find this mark a convenience as it enables me to put the two cards in proper position more readily. The inspector then punches the first unit space B on both cards, this punch mark showing at T on card P and T' on card Q. In practice I make this punch mark T of a peculiar shape, so that it may be readily distinguishable from other punch marks on the card. This mark serves to indicate that no payments are to be made in excess of the 80 total figure below this punch mark.

If it is desired to make a second subtraction from the card, it may be made in the same manner as that in which additions to the card are made. I will not, therefore, describe it further.

The subtraction cards which I have just 100 described are a form of secondary card and upon them is kept the duplicate record of subtractions corresponding with the subtractions which have been made on the workman's time or primary cards. The 105 subtraction cards go to the treasurer and become his voucher for this amount of money which is not paid to the men, to help balance the envelopes which are charged to him at full face value without any deductions.

What I claim is;

1: In an accounting system and in combination, a primary card having spaces arranged in a plurality of columns of equal height, furnished with progressive numerals, 115 beginning at a predetermined starting point and following a predetermined path, the centers of said spaces along the said path being equidistant from each other, and a secondary card having spaces similarly arranged whose 120 centers are adapted to register with the centers of the said spaces on the primary card, said spaces being also provided with numerals, each of which is a multiple of the number of the space to which it is applied, the number 125 of said space being counted from a predetermined point along a predetermined path, which point and path register with the first mentioned point and path.

2. In an accounting system and in combi- 130

- nation, a card or slip provided with spaces progressively numbered, beginning at a predetermined starting point and following a predetermined path, the centers of said spaces along the said path being equidistant from each other, one or more other cards or slips similarly provided with spaces whose centers are adapted to register with the centers of the spaces on the first mentioned card and having a set of numerals for the said spaces, each of which is a multiple of the number of the space to which it is applied, the number of said space being counted from a predetermined starting point along a predetermined path which register with the first mentioned point and path, the spaces on all the cards comprising the system being arranged in columns of equal height, and punch marks by which a point on each of two or more cards is simultaneously indicated.
3. An accounting system comprising cards of different kinds, some of which are provided with consecutively numbered unit spaces of uniform size, and others of which are provided with spaces which are in size multiples of the said unit spaces and are provided with numerals such as are commonly used to denote the hours of the working day,
- all the spaces on any card being the same size and arranged in columns of equal height.
4. In an accounting system and in combination, a primary card having spaces arranged in a plurality of columns of equal height, furnished with numerals, such as are commonly used to denote the hours of the working day, said numerals beginning at a predetermined starting point and following a predetermined path, the centers of said spaces along the said path being equidistant from each other, and a secondary card having spaces similarly arranged whose centers are adapted to register with the centers of the said spaces on the primary card, said spaces being also provided with numerals, each of which is a multiple of the number of the space to which it is applied, the number of said space being counted from a predetermined point along a predetermined path, which point and path register with the first mentioned point and path.

In testimony whereof I affix my signature, in presence of two witnesses.

EDWARD C. ALBREE.
